UNITED STATES PATENT OFFICE

163,803

TOY CANDY SHOP

John W. Hazelton, Toronto, Ontario, Canada

Application March 21, 1950, Serial No. 8,663

Term of patent 3½ years

(Cl. D34—15)

To all whom it may concern:

Be it known that I, John W. Hazelton, a citizen of Canada, residing at Toronto, in the county of York and Province of Ontario, have invented a new, original, and ornamental Design for a Toy Candy Shop, of which the following is a specification, reference being had to the accompanying drawings, forming a part thereof.

The figure is a perspective view of the toy candy shop showing my new design.

In the drawing the figure is lined to represent the color red. The right end of the toy candy shop is identical with the end shown and the rear is devoid of ornamentation.

I claim:

The ornamental design for a toy candy shop, substantially as shown and described.

JOHN W. HAZELTON.
